ESCUTCHEON PLATE

John R. Morgan, Wheeling, Ill., assignor to Amerock Corporation, Rockford, Ill., a corporation of Illinois

Filed May 14, 1963, Ser. No. 74,873

Term of patent 14 years

(Cl. D50—6)

FIG. 2 is a side view of the plate.

FIG. 3 is a sectional view taken along the line 3—3 in FIG. 1.

FIG. 4 is a sectional view taken along the line 4—4 in FIG. 1.

FIG. 5 is a sectional view taken along the line 5—5 in FIG. 1.

FIG. 6 is a sectional view taken along the line 6—6 in FIG. 1.

FIG. 7 is a sectional view taken along the line 7—7 in FIG. 1.

I claim:

The ornamental design for an escutcheon plate, substantially as shown.
